UNITED STATES PATENT OFFICE.

JOSHUA W. ATLEE, OF RIVERTON, NEW JERSEY.

LAVATORY.

1,129,325.

Specification of Letters Patent. Patented Feb. 23, 1915.

Application filed March 18, 1914. Serial No. 825,442.

To all whom it may concern:

Be it known that I, JOSHUA W. ATLEE, a citizen of the United States, and a resident of Riverton, county of Burlington, State of New Jersey, have invented certain new and useful Improvements in Lavatories, of which the following is a specification, reference being had to the accompanying drawing.

Among the principal objects of my invention are to provide an improved form of lavatory especially adapted for use on shipboard; to provide a lavatory which may be readily suspended to the wall or side of the room, building or vessel in which it may be used, and which may be readily detached therefrom for cleaning or repairs; and to provide a lavatory in which the basin and supply tank from which the fluid for use in the basin may be drawn shall be in integral relation, so that the whole shall form a unitary fixture of great strength, and in which each of the several elements of the device shall serve to strengthen, reinforce, and support the other elements thereof.

Further objects of my invention are to provide an improved lavatory having a supply tank and basin in integral relation, which shall be attractive in appearance; which may be readily cleaned; and in which the water or other liquid for use therein may be readily introduced within the tank, and from which it will not be apt to overflow owing to the motion of the vessel on which the lavatory may be used.

Still further objects of my invention are to provide such a lavatory especially adapted for use on shipboard, from the tank of which water may be continuously withdrawn, even though the vessel be rolling; which shall be strong in construction, not liable to get out of order, and which shall present a pleasing and attractive appearance to the eye.

My invention further includes all of the other various novel features of construction and arrangement hereinafter more definitely specified.

Referring to the drawing, Figure 1 thereof is a top plan view of one form of lavatory constructed in accordance with my invention; Fig. 2 is a side elevation thereof partially in vertical section taken along the line 2—2 of Fig. 1 looking in the direction of the arrows; and Fig. 3 a fragmentary front elevation of the lavatory, removed from its

supports and also partially in vertical section.

That embodiment of my invention illustrated in the drawing may consist of a basin 1 of suitable size and shape, the form illustrated being substantially oval at the top and having the sides and bottom curved substantially as shown. The specific form of the basin, however, forms no part of my invention, as any suitable shape may be used. 60 The basin may be provided as usual with an outlet 3 adapted for the insertion of a suitable plug 4, which may, if desired, be attached to the end of the chain 5 in the usual manner. A suitable slab 7 may be 65 formed around the sides and front of the basin and may, if desired, be provided with one or more depressions 9, provided with the raised ridges 10 adapted to support a cake of soap thereon. Suitable drainage ducts 12 70 may lead from the depression 9 into the basin, for the purpose of carrying off superfluous water.

Located at the rear side of the basin 1 and above the level of the slab 7 is the tank 15, 80 having a front wall 17, end walls 18 and 19, a rear wall 20, and bottom 21. This tank may extend substantially across the greatest width of the slab 7, and may be of any desired height and depth, although a tank of 85 substantially the relative proportions of that shown in the drawing has been found in practice to give satisfactory results. The tank may be provided with a top 24 filling the space between the sides, front and rear 90 of the tank, around which may be preferably worked a suitable beading 26, and having, preferably at its approximate center, a filling aperture 28, closed by a suitable removable plate 30, provided with a convenient handle 31. The plate 30 may be 95 preferably constructed as shown and arranged to fit snugly within the aperture 28, a suitable flange 32, adapted to rest upon the surface of the top 24, preventing the plate 100 from passing through the aperture 28. Suitable webs 35 may be provided between the sides of the slab 7 and the front 17 of the tank, preferably in substantial vertical alignment with the end walls thereof, these 105 webs being operative to assist in supporting the slab 7, and basin 1, as well as adding to the appearance of the device. Around the periphery of the slab 7 and extending rearwardly to the plane of the rear face of the 110

wall 20, a depending apron 37 of any desired depth and thickness may preferably be formed, this apron serving to strengthen and support the slab 7 and the other parts 5 of the device, as well as adding to the attractive appearance thereof. This apron at the sides of the slab may preferably be in substantial vertical alinement with the webs 35. A suitable web 42 may be provided extending downwardly from the bottom 21 of 10 the tank 15, and serving to support the rear side of the basin 1.

The lavatory may be suspended or attached to the wall 40 of the room in which 15 it is located in any desired manner, either permanently or detachably. I prefer, however, for the purpose of best effecting the objects of my invention, to removably support the same in the manner illustrated in the 20 drawing, such support being effected by means of a pair of suitable brackets 50, rigidly attached to the wall 40 by means of suitable screws or other attaching means 51. While the brackets may be of any desired 25 form or construction, they may each preferably consist of a base plate 54, having suitable apertures for the passage of screws 51, as well as a suitable lug 55 of preferably substantially rectangular cross-section projecting 30 from the inner side of the base 54 and adapted to enter a suitable aperture formed in the wall 40, for the purpose of steadyng the bracket and assisting the screws 51 in holding it fixedly in position, 35 while projecting obliquely upwardly from the outer side of the base plate 54 is a suitable lug 58, also preferably of substantially rectangular cross-section, which may be provided with a somewhat flexible surrounding 40 cushion 59, permanently attached thereto.

Preferably adjacent each of the end walls of the tank 15, and in the rear wall thereof, a slot 60, suitable for the reception of the lug 58 with its surrounding cushion 59 may 45 be provided, such slot being formed between the inside of the end wall of the tank and the side of a vertical partition 62 extending between the front and rear walls of the tank, an oblique partition 64 forming 50 the front wall of the slot. The slot itself extends obliquely upwardly above the upper end of the partition 64, the space between the front wall 17 and the rear wall 20 of the tank at this point being filled in and 55 made solid as clearly shown in Fig. 2. The material of which the lavatory is constructed is so molded or otherwise formed as to provide a suitable depending dog 68, adapted to enter the V-shaped space formed between 60 the upper side of the cushion 59 and the front of the base plate 54 of each bracket, whereby the lavatory will be suspended from the brackets, the angle of inclination of the lug 58 being such that the force of 65 gravity acting in a downward direction will

tend to draw the dog 68 tightly into the V-shaped space between the cushion 59 and the front of the base plate 54, whereby the rear wall of the lavatory will be forced snugly against the supporting wall 40.

70

As the slots 60 are preferably spaced as far apart as is possible within the limits of the device, and the brackets 50 arranged accordingly, it will be evident that the lavatory will be maintained most securely in position against the supporting wall 40, from which it may readily be detached by lifting it upwardly and forwardly so that the point of the dog 68 will pass over the upper extremity of the cushion 59, after which the lavatory will be completely clear of any attachment to the wall 40.

75

For the purpose of withdrawing the water or other fluid which may be contained in the tank 15, a suitable faucet 72 may be provided near the bottom of the tank, and preferably equi-distant of its ends, and a suitable receptacle 75 may be located beneath the lower end of the vent 3 for the reception of the waste water, or the vent 3 may be connected with a waste pipe as may be desired. By locating the faucet 72 as herein described, it is possible to draw water from the tank in a continuous stream, even though the vessel on which the lavatory is used may be "heeled" to a considerable angle, since, even if only a small quantity of water be contained in the tank the inner end of the faucet will be always immersed. Furthermore, if desired, a suitable rail 80 may be 100 attached to the wall 40 above the top of the tank whereby a glass or other article 81 placed upon the top of the tank, which affords a convenient resting place for such articles, will be maintained in an upright position and prevented from displacement from the rolling of the vessel upon which the lavatory may be used.

85

From the foregoing description, it is believed that the operation of the device will 110 be evident, but also it is considered advisable to point out that by locating the filling aperture 28 in the top 24 of the tank, I generally find it unnecessary to make the fit between it and the cover plate 30 a watertight one, which would be necessary were the aperture located near one end of the tank, since the rolling of the vessel in such case would tend to frequently immerse the inside of the cover plate, whereby the liquid 115 would be forced out around the edges thereof if it did not form a water tight joint in the aperture 28. It will be further evident that the lavatory may be constructed of any suitable material, such as porcelain, earthenware or other porcelaneous material, cast-iron, or other metal. In constructing the same of porcelain or other earthenware, however, it will probably be necessary in practice, as is usual in the manufacture of 120

115

125

130

articles of this nature, to first form the device in several separate parts, which parts may then be jointed together and fused into an integral whole in a suitable kiln, and I, therefore, when describing my improved lavatory as an "integral or unitary device" must be understood as referring to the finished article, and not to the article during its course of manufacture. Furthermore, I 10 do not desire to limit myself to the precise details of construction and arrangement of that form of my invention which I have herein illustrated and described, as it will be evident that various changes may be 15 made in the details and arrangement of the various parts of the device without departing from the spirit and scope of the invention as defined in the appended claims.

It is also to be understood that when desired the whole device may be substantially locked in position against the wall by inserting a screw 38 through the flange 37' at the rear of the basin, which would prevent the device from being lifted from off 25 the lugs 58, and thus prevent any accidental detachment of the device from the wall.

Having thus described my invention, I claim and desire to protect by Letters Patent of the United States:

30 1. In a lavatory, the combination of a tank, means to attach said tank rigidly to a substantially vertical support, a slab extending outwardly from substantially the front edge of the bottom of said tank integral 35 with and supported by said tank, a wash basin integral with said slab, and stiffening webs extending between the front ends of said tank and the top side edges of said slab and integral with said tank and slab.

40 2. In a lavatory, the combination of a tank, means to suspend the tank from a substantially vertical support, a slab extending outwardly from substantially the front edge of the bottom of said tank integral 45 with and supported by said tank, a wash basin integral with said slab, stiffening webs

extending between the front ends of said tank and the top side edges of said slab and integral with said tank and slab, and a 50 stiffening edge integral with said slab and tank and extending around said slab.

3. In a lavatory, the combination of a tank, means to suspend the tank from a substantially vertical support, a slab extending 55 outwardly from substantially the front edge of the bottom of said tank integral with and supported by said tank, a wash basin integral with said slab and stiffening webs extending between the front ends of said tank 60 and the top side edges of said slab and integral with said tank and slab, and an apron integral with said slab and tank and depending from the edge of said slab and the sides of said tank.

65 4. In a lavatory, the combination of a tank, means to suspend said tank from a substantially vertical support, a slab extending outwardly from substantially the front edge of the bottom of said tank and supported by 70 said tank, a wash basin, stiffening ribs extending between the front ends of said tank and the top side edges of said slab and a stiffening edge extending around the front and side edges of said slab, said tank, slab 75 and basin, webs and stiffening edge being integral and of porcelaneous material.

5. In a lavatory, the combination of a tank, means to suspend said tank from a substantially vertical support, a slab extending 80 outwardly from substantially the front edge of the bottom of said tank, integral with and supported by said tank and forming substantially a continuation of the bottom wall of said tank, and a wash basin integral 85 with said slab and depending below the top surface of said slab.

In witness whereof, I have hereunto set my hand this seventeenth day of March, A. D. 1914.

JOSHUA W. ATLEE.
